G. G. PAIN

SHUTTLE CASING FOR SEWING MACHINES

Filed April 4, 1923

INVENTOR:

George G. Paine

BY, Allen & Allen
ATTORNEYS.

UNITED STATES PATENT OFFICE.

GEORGE G. PAINE, OF LUDLOW, KENTUCKY.

SHUTTLE CASING FOR SEWING MACHINES.

Application filed April 4, 1923. Serial No. 629,747.

To all whom it may concern:

Be it known that I, GEORGE G. PAINE, a citizen of the United States, and a resident of Ludlow, in the county of Kenton and State of Kentucky, have invented certain new and useful Improvements in Shuttle Casings for Sewing Machines, of which the following is a full, clear, and exact description, reference being had to the accompanying drawing, forming part of this specification.

The object of my invention is to improve the shuttle holder for the Singer type of sewing machines and particularly for that type of Singer machine employed for automatic tacking in which the machine upon being started takes a limited number of stitches, stops automatically and cutting knives then automatically sweep across the top of the race-way and sever the needle and the bobbin thread.

In the construction of shuttle race heretofore employed in such machines the shuttle holder is cut away entirely at the top to provide sufficient space for the point of the shuttle to catch and throw off the loop of the thread and the cutting knives play across this open space, or where an attempt has been made to bridge the open space partially by a bridge plate it has always been found difficult to prevent the thread from becoming jammed at the corner of the bridge and to maintain sufficient tautness of the thread to permit the knives to sever the thread close up to the goods.

Heretofore frequent trouble has been experienced in the operation of such automatic tacking machines by the threads catching and breaking or by the knives failing to sever the threads close to the goods.

It is the object of my invention to overcome these defects and to provide a construction in which the liability of the threads catching or the knives failing to cut the thread off short is reduced to a minimum.

This I accomplish by that certain novel construction to be hereinafter particularly pointed out and claimed in the specification and claims that follow.

In the drawings:

Figure 1 is a perspective view of my improved construction showing the location and relative position of the cutting knife mechanism.

Figure 2 is a similar perspective view of the construction taken from the inside.

The shuttle holder 1 is of the usual circular form provided with an internal peripheral groove 2 within which is seated the shuttle 3 adapted to oscillate in the race and driven by mechanism not shown. The shuttle 3 has the pointed end 4 to enter and pick up the thread loop for throwing over the shuttle and it carries the bobbin case 5 which is held in position by the bobbin arm 6 which engages in the slot 7 in the casing, while the bobbin 8 is free to rotate in the bobbin case.

The top portion of the shuttle casing is cut away to leave a flat top 9 with an open space over the bobbin case and this space is partly covered by a bridge plate 10, substantially a rectangular plate with a beveled corner 12 so that the point 4 of the shuttle in picking up the loop will carry the thread without any liability of catching over the smooth slightly raised surface 13 of the casing and around the shuttle. Heretofore there has always been a chance that the thread would catch in some sharp corner as it was caught up by the shuttle, but my bridge plate with its diagonal edge merging into the smooth surface of the casing effectually prevents this.

The sewing needle carrying the needle thread, reciprocates back and forth through the hole 14 in the top plate 15 which is set in the top of the machine and upon which the goods to be sewed are fed, and the shuttle holder and other parts heretofore described are mounted in fixed position by the screws 16, 16, in proper position for the needle action.

Underneath the plate 15 is secured the cutting knife 17 for severing the needle and bobbin threads at the end of each sewing operation. This construction is old and forms no part of my invention and I have, therefore, merely indicated the location of the mechanism omitting the driving connections. I will make no attempt to describe this mechanism in detail, other than to say that at the proper time the cutting knife is operated automatically by mechanism not shown to swing across the top face 9 and the bridge plate 10 to sever the threads. As heretofore constructed, however, the sweep of the knife tends to carry the threads into

some sharp corner and either wedges the thread or the action tends to draw on the threads and not to sever them sharply with only short ends.

- 5 To remedy this defect I form a smooth upwardly extending groove 18 along the side face of the casing terminating in a transverse groove 19. The edges of these grooves are smooth so as not to present any sharp 10 surface with the bridge plate terminating at the edge of the grooves, and the threads as they are met by the sweep of the knife are carried into these grooves so that there is no liability of catching and pulling out 15 and a clean cut is made by the knife, leaving very short ends.

Having thus described my invention, what

I claim as new and desire to secure by Letters Patent, is:—

In a device of the character specified, the 20 combination of a flat topped shuttle casing, a shuttle, a bridge plate, an admission aperture for a threaded needle in the shuttle casing, and a thread cutting knife, said flat topped casing cut-away adjacent the admission aperture, a diagonally edged bridge plate disposed on the flat topped shuttle casing, a radial groove at the front edge of the bridge plate and a transverse groove on the top of the casing adjacent the radial 25 30 groove whereby said grooves receive the cut thread from the needle.

GEORGE G. PAYNE.
